Patented Feb. 21, 1922.

UNITED STATES PATENT OFFICE.

HARRY O. PRATER, OF CLAYTON, WASHINGTON.

STEAM BOILER.

1,407,217.

Specification of Letters Patent. Patented Feb. 21, 1922.

Application filed October 4, 1920. Serial No. 414,532.

To all whom it may concern:

Be it known that I, HARRY O. PRATER, a citizen of the United States, residing at Clayton, in the county of Stevens and State 5 of Washington, have invented certain new and useful Improvements in Steam Boilers, of which the following is a specification.

The present invention relates to improvements in steam boilers of the water tube or 10 tubular type involving the utilization of upper and lower horizontal headers and vertical water tubes. The primary object of the invention is the provision of a structure of this nature in which the tubes may with facility be installed and the boiler erected 15 quickly and conveniently without the use of skilled labor or special tools or equipment, and the tubes may with equal facility be displaced and withdrawn when required. By 20 the novel construction of the water tubes and their connection with the headers, the tubes may be cleaned while in situ, or when required a tube may be removed and replaced without disturbing the remainder of the 25 structure.

To this end the invention contemplates the utilization of a novel form of water tube having threaded portions for the respective headers so arranged and constructed that 30 the tube may be threaded into both headers simultaneously. Other meritorious features reside in the means establishing communication between the water header and steam header and tubes, in the provision for cleaning 35 the tubes, and in other details of construction as will be hereinafter pointed out and claimed.

In the accompanying drawings I have 40 illustrated one complete example of the physical embodiment of my invention wherein the parts are combined and arranged according to the best mode I have thus far devised for the practical application of the principles of my invention.

45 Figure 1 is a view partly in perspective and partly in section, showing a portion of a tubular boiler according to my invention.

Figure 2 is a front elevation of a boiler 50 embodying the invention, a portion of the tubes being eliminated for convenience of illustration.

Figure 3 is an enlarged view of a detached tube, partly in section to disclose the construction thereof.

55 In the preferred form of the invention as

illustrated in the drawings the boiler is of the vertical tubular type utilizing the lower header 1 as a water chamber, and the upper header 2 as a steam chamber, the water feed pipe 3 entering the water chamber at the lower end of the boiler, and the steam pipe 4 being adapted to conduct steam from the steam chamber 5 formed in the header 2. The headers are each made up of integral cast plates of proper form and size, and hollow to form the water chamber 3^a and the steam chamber 5, and as shown in the drawings the headers are arranged in parallelism and horizontal and suitably supported in the furnace structure in position to receive heat 70 on the exterior of the connecting water tubes 7.

The water tubes connect the two headers and are arranged vertically therebetween, preferably in diagonally extending lines as 75 indicated, to permit free access and passage of the gases of combustion from the furnace to heat the tubes and headers. Each tube is installed separately, and is jointed simultaneously to the headers by means of a socket 80 wrench, and to accomplish this purpose the heavy tubes are each provided with a closed lower end having a squared head 7, and provided with external screw threads 8 extending a suitable distance above the squared 85 head. Near the lower end of the tube an inlet port or orifice 9 is provided extending transversely through the wall of the tube and in position to provide communication between the water chamber 3^a and the interior 90 of the tube.

The upper end of the tube is equipped with external threads 10 which are of exactly the same pitch as the threads 8 at the lower end of the tube, but of greater diameter, thus 95 permitting the lower threaded end of the tube to be passed through the socket in the header 2, which socket is larger than the socket in the header 1, and as the two series of threads are of the same pitch, the tube 100 may be turned in its two threaded headers to be secured in place. An outlet port 12 is depicted in the upper end of the tube in Figure 3 to pass steam from the upper portion of the tube to the steam chamber 5 in the header 105 2, and this port is also positioned to open into the steam chamber when the tube is in proper location between the headers. At its upper extremity the tube is fashioned with a reduced squared head 10', which is bored 110

and drilled to aline with the bore of the tube, as at 11, and this hole is threaded to receive a closure or plug 13, as shown in Figure 3.

The sockets or tube holes in the respective headers are drilled or bored according to complementary diagrams, and in the erection of the structure, the lower end of the tube which has threads of less diameter than the threads at its upper end, is passed through 10 the larger socket or tube opening in the header 2, and inserted in the smaller socket in the header 1. With the smaller and larger threads engaging the walls of their respective sockets, a socket wrench is applied to 15 each of the squared heads 7 and 10' and the tube is turned, without twisting or undue strain, to enter its complementary sockets in the headers, leaving the orifices or ports 9 and 12 in communication with their respective chambers in the headers. After the tube is placed, the screw plug 13 may be threaded 20 into the head 10' to seal the top of the tube. The tubes are sealed in their sockets in the headers with usual packing or compounds to 25 make water tight and steam tight joints, and the structure forms a compact and rigid appliance for the generation of steam which is formed in the upper portion of the tubes and

passes through the steam chamber 5 and thence through the steam pipe 4 for use, under suitable regulation means. 30

For the purpose of cleaning the tube while in situ the plug 13 may be removed and a tube cleaning tool be inserted in the tube from the upper end to scrape off deposits of lime &c to be later washed out in usual manner. In removing a tube, the socket wrench is applied at both ends simultaneously and power is thus exerted on both threaded joints to start the tube and render its turning easy 40 and uniform.

Having thus fully described my invention, what I claim as new and desire to secure by Letters Patent is—

The combination with spaced headers having sockets of different diameters and forming a water chamber and a steam chamber, of water tubes, each having ports communicating with each chamber and threaded portions of the same pitch complementary to 50 said sockets, tool heads on the end of each tube projecting beyond the respective headers, and an alined socket and screw plug in one of said tool heads. 45

In testimony whereof I affix my signature. 55

HARRY O. PRATER.
